WIRE STRETCHER

Filed Sept. 5, 1922

Inventor
Louis F. Wallen
By *Grace C. Wallen*

Attorney

UNITED STATES PATENT OFFICE.

LOUIS F. WALLEN, OF WILSONVILLE, NEBRASKA.

WIRE STRETCHER.

Application filed September 5, 1922. Serial No. 586,272.

To all whom it may concern:

Be it known that I, LOUIS F. WALLEN, a citizen of the United States, residing at Wilsonville, in the county of Furnas, State 5 of Nebraska, have invented certain new and useful Improvements in Wire Stretchers; and I do hereby declare the following to be a full, clear, and exact description of the invention, such as will enable others skilled 10 in the art to which it appertains to make and use the same.

This invention relates to new and useful improvements in stretching devices and particularly to devices for stretching telephone, 15 telegraph, and electric light wires.

One object of the invention is to provide a simple and efficient device by means of which telephone and the like wires may be stretched, without the use of rope devices 20 heretofore used, and with better results, and without injury to the wires.

Another object is to provide a simple and compact device of this character, and one which can be easily operated by one man.

25 Other objects and advantages will be apparent from the following description when taken in connection with the accompanying drawing.

In the drawing:

30 Figure 1 is a side elevation of a wire stretcher made in accordance with the invention.

Figure 2 is a vertical transverse sectional view through the device, on the line 2—2 of 35 Figure 1.

Referring particularly to the accompanying drawing there is shown an elongated frame consisting of the upper and lower longer bars 10 held in spaced relation by the 40 transverse bars 11, which are secured to and extend between the ends of the longer bars. Carried on one of the end bars 11 is a hook 12 which is adapted to be engaged with a suitable support, while a wire clamp 13 is 45 carried by the other end bar 11. Slidably longitudinally in the space between the longer bars 10 is a shorter bar 14, the end adjacent the hook carried bar 11 carrying a wire clamp 15, similar to the clamp 13, 50 and being in longitudinal alignment therewith.

Pivots connected to the cross bar 11 which carries the hook 12, is one end of a link 16, the other end being pivotally con-

nected to the lower end of a vertical lever 55 17. This lever is pivotally connected with the end of the slidable bar 14, remote from the clamp 15, whereby when said lever is rocked in one direction it moves the bar 14 toward the hook end of the frame, causing 60 the clamp 15 to draw the wire, the wire sliding through the other clamp 13. When the lever is moved in the other direction it moves the bar 14 toward the clamp 13, said clamp firmly holding the wire, while the 65 wire is permitted to slide through the clamp 15. Thus, by rocking the lever back and forth, the wire may be drawn to the desired tension. The link 16 compensates for the up 70 and down movement of the lower end of the lever, as the lever is rocked back and forth, thereby obviating the necessity of providing any slots in the parts. Furthermore, the link serves to anchor the lever to the end of the frame, with the result that as the lever is 75 rocked, the frame is moved in one direction while the bar 14 is moved in the opposite direction.

Secured to the clamp carrying end of the bar 14, and extending transversely of the 80 opposite outer faces of the bars 10, are the transverse guide strips 18, which hold the said end of the bar against movement from between the bars 10.

Pivots mounted on the upper ends of 85 the strips 18, and straddling the upper bar 10, is a hand grip 19, the same being connected to the pivoted jaw 13' of the clamp 13, for releasing the jaw from the wire. A similar hand grip 20 is pivotally mounted 90 on the hook end of the frame and is pivotally connected with the jaw 15' of the clamp 15, for the same purpose.

What is claimed is:

A wire stretcher comprising a frame including parallel bars having terminal connecting and spacing members, a shorter bar disposed for longitudinal slidable movement between the parallel bars, transverse members on one end of the shorter bar and having their ends extended across the wider faces of the parallel bars, a link pivotally connected to one of said spacing members, a lever intermediately pivoted to the other end of the shorter bar and having one end pivotally connected with the other end of the link, a wire clamp on the shorter bar intermediate the lever and the transverse members, a hand

lever on one of the transverse members and operatively connected with the clamp, a clamp on one of the spacing members, a hand lever on one of the parallel bars adjacent the 5 spacing member which carries the link, and a link between the last hand lever and the last clamp.

In testimony whereof, I affix my signature, in the presence of two witnesses:

LOUIS F. WALLEN.

Witnesses:

F. R PARKER,
E. J. HAMILTON.
